UNITED STATES PATENT OFFICE.

GEORGE H. HOLLAND, OF ST. LOUIS, MISSOURI, ASSIGNOR TO THE BRIDGE & BEACH MANUFACTURING COMPANY, OF SAME PLACE.

DESIGN FOR A HEATING-STOVE.

SPECIFICATION forming part of Design No. 22,574, dated June 27, 1893.

Application filed May 26, 1893. Serial No. 475,643. Term of patent 7 years.

To all whom it may concern:

Be it known that I, GEORGE H. HOLLAND, a citizen of the United States, residing at St. Louis, State of Missouri, have invented and 5 produced a new and original Design for Stoves, of which the following is a full, clear, and exact description, reference being had to the accompanying drawing, wherein the figure represents a perspective view of a stove ornamented with my new design.

This design relates particularly to an upright, square-shaped stove and consists in the shape and ornamentation of its several component parts, as will hereinafter be described.

15 The base is square shaped having its upper surface rounded and ornamented with a number of leaves, the stems of which intertwine. This base is mounted upon a similarly shaped sub-base, from the corners of which project 20 the legs, said legs being ornamented on their outwardly curving surfaces, with a leaf arranged about the center thereof. Arranged at each side of the legs on the sub-base is a large scroll having several smaller scrolls and 25 a spray leading therefrom, the two large scrolls on each side curving upwardly and across to meet each other to form a panel, in which panel are leaves having their stems crossed. Projecting laterally from the upper 30 of the base are foot rests in the shape of logs of wood, around which stems and leaves are helically arranged. The ash pit door has the usual draft openings, between, and on each side of which are scrolls. Raised panels are 35 arranged at the side of the ash box which panels are ornamented with leaves and their stems. A flange extends out over the ash pit door, which flange is ornamented with curved transversely arranged flutes, the upper ends 40 of which are turned back to form nubs or scrolls. Above this flange, on the front of the stove, is a door having the usual openings, and at the sides of the stove are arranged similar doors on about the plane with the one 45 above mentioned. Projecting downwardly

and outwardly from the body of the stove from a point above these doors, is a flange which is ornamented on its upper curved surface with scrolls. The front and sides of the stove above this flange are provided with 50 doors having two rows of openings as shown, and above these doors are arranged raised panels, ornamented with scrolls at their sides, which scrolls extend across at the upper edges of the panels to meet each other, leaving spaces 55 between for names or numbers.

At the back of the body of the stove is a heating drum extending nearly its entire length, terminating at its upper edge slightly below the top of the stove body in a heating 60 chamber, from which projects rearwardly, the cylindrically shaped pipe elbow.

The top portion of the stove projects over the body, its lower side being curved to meet the front, sides, and back of the body portion, 65 said curved portion being ornamented with scrolls. The upper of this top is formed rounded, and is ornamented with scrolls at its corners which form panels, in which panels are arranged leaves having their stems crossed. 70 Arranged at the upper portion of this top, is a dome-shaped cap piece which is ornamented with leaves having their stems intertwined. On the top of this dome is a cylindrically shaped urn, having its top portion fluted, and 75 a top piece in the form of spraying leaves or petals. The body portion of the urn is ornamented with a spray of pointed leaves, and has arranged at its sides, dragons forming handles.

80 What I claim is—

The herein described design for stoves, substantially as shown.

In testimony whereof I hereunto affix my signature, in presence of two witnesses, this 85 17th day of May, 1893.

GEO. H. HOLLAND.
